US00D519735S

(12) **United States Design Patent** (10) **Patent No.:** **US D519,735 S**
Bentley et al. (45) **Date of Patent:** **** May 2, 2006**

(54) **CLOTHES HANGER STORAGE DEVICE**

(75) Inventors: **Renee M. Bentley**, 2155 N. Glennfield Way, Meridian, ID (US) 38642; **Taylor Jenkins**, Nampa, ID (US)

(73) Assignee: **Renee M. Bentley**, Meridian, ID (US)

(**) Term: **14 Years**

(21) Appl. No.: **29/218,351**

(22) Filed: **Nov. 30, 2004**

(51) **LOC (8) Cl. 03-01**

(52) **U.S. Cl. D3/304**

(58) **Field of Classification Search** D3/20, D3/200, 201, 203.1, 203.3, 205, 206, 273, D3/276, 304-315; D6/525, 475, 476; D19/75, D19/77, 86, 90, 92, 100; 206/203, 214, 215, 206/822, 307.1; 229/100, 914, 913, 406

(57) **CLAIM**

The ornamental design for an clothes hanger storage device, as shown and described.

DESCRIPTION

FIG. 1 is a front perspective view of a clothes hanger storage device showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a front perspective view thereof with brackets; and,

FIG. 9 is a front perspective view thereof with a lid. The broken line showing of brackets and a lid in FIGS. 8 and 9 is for illustrative purposes only and forms no part of the claimed design.
